UNITED STATES PATENT OFFICE.

SIMEON H. RICKARD, OF FREEDOM, PENNSYLVANIA.

CONVEYING AND ELEVATING APPARATUS.

Application filed May 23, 1922. Serial No. 563,010.

To all whom it may concern:

Be it known that I, SIMEON H. RICKARD, a citizen of the United States, residing at Freedom, in the county of Beaver and State 5 of Pennsylvania, have invented certain new and useful Improvements in Conveying and Elevating Apparatus, of which the following is a specification.

My invention is an improvement in conveying and elevating apparatus for loose material, as coal and the like. The invention refers to the general arrangement of the conveying and elevating apparatus, and particularly to the construction of the chain 10 links for the flights or buckets, the sprocket wheels therefor, the elevator boot, and various other features as shall be more fully hereinafter set forth.

In the drawings, showing the invention in 20 some of its various possible installations,

Fig. 1 is a general sectional elevation, partly broken away, showing a conveyor and elevator constructed for continuous operation and utilizing the invention;

Fig. 2 is a sectional plan view on the line II—II of Fig. 1;

Fig. 3 is an enlarged detail view in elevation, showing the mounting of the conveyor chain on the lower sprocket, and the 30 form of the elevator boot;

Fig. 4 is a plan view of Fig. 3;

Fig. 5 is a sectional view on the line V—V of Fig. 3;

Fig. 6 is a detail view of connected strands 35 of the conveyor and elevator chain as used;

Fig. 7 is an edge elevation of Fig. 6;

Fig. 8 is a cross section on the line VIII—VIII of Fig. 6;

Fig. 9 is a partial sectional view, similar 40 to Fig. 1, showing a modified construction of conveyor for use underneath a car; and

Fig. 10 is a cross section on the line X—X of Fig. 9.

The movable element of the invention 45 which contributes to its special efficiency for conveying and elevating loads of loose material, is a chain of special construction, composed of oppositely arranged pairs of links, pivotally connected successively to 50 similar pairs, each pair including an inwardly or outwardly flanged link adapted for connection with the flight or bucket, and capable of traveling around special sprocket wheels and in guiding tracks.

55 In the drawings, A is a conveyor arranged longitudinally in a suitable pit *a* underneath

a railroad track 2, 2, for receiving the contents of a car 3 thereon. The conveyor A is designed to deliver material, as coal, in the hopper 4 of an elevator boot 5 from which it 60 is removed by the buckets of an elevator B arranged to discharge at its top through a suitable chute into a receiving hopper or bin.

The frame of conveyor A consists of upper and lower angle members 6, 7, framed 65 together and spaced apart the proper distance to provide by their lower inwardly extending flanges, supporting trackways for the lower edges of the chain links. The vertical angles provide outer guideways between which, above and below, the chain links and their flights pass in load-supporting and return movement.

The elevator B is similarly constructed of angle members 8, 9, also suitably braced by 75 lattice bracing, as shown, and providing by their flanges guiding and retaining trackways in the same way.

The head shaft 10 of conveyor A is geared with the foot shaft 11 of elevator B by 80 sprocket gearing and chain 12, and the head shaft 13 of the elevator is preferably geared by sprocket gearing with any suitable similar gearing, as a chain in driving connection with wheels 14—15 which are in driving connection with an engine, as will be readily understood. The chain 12 may be of the same construction as the conveyor and elevating chains, without the flange, together with similar driving and driven 85 sprockets. Ordinarily, a clutch *b* is interposed between the foot shaft 11 and the driving sprocket *d* of chain 12, so that the operator may control the conveyor to prevent overloading of the elevator boot in case of 90 any surplus supply being delivered to the conveyor.

Referring more particularly to the chain construction, it consists of pairs of outer and inner links 16—17 in overlapping 100 pivotal connection with similar adjacent links, off-set to a distance equalling the thickness of the links alternately, as shown in Fig. 6. Each inner link has an inwardly extending flange 18 terminating inwardly of each rounded end and provided with rivet or bolt holes 19 for attachment of the flights or rear walls of the buckets, of the conveyor or elevator respectively. The ends of the links 16—17 are provided with 105 holes for insertion of connecting bolts or pins 21 having outer heads 22 providing

flexible joints for passage around the sprocket wheels 23 of shafts 11 and 13. The bolts or pins 21 are preferably of softer steel than that of the links, so as to avoid impairment of the holes by undue wear, the pins being renewed from time to time. Said sprocket wheels as shown are square, one for each double strand chain, and each has an outer circular flange 24 providing for embracing and guiding engagement with the outer sides of the links. In this respect the sprocket flanges 24 are in edge alignment with the flanges of angle members 8-9, so as to ensure tracking of the links in passing from the other supporting flange of said angle members on to the sprocket wheels, or vice versa.

Referring to the elevator, the buckets are formed of a back wall 25 of sheet or plate metal, similar sides 26-26, and an outer front wall 27, exactly the same as the back wall 25, diverging upwardly from the bottom, as shown. Sides 26 have inwardly extending flanges 28-29, and the inner flanges 28 are connected directly with the back wall 25 and with flanges 18 of the inner links by rivets or bolts 30 extending through suitable holes in the bucket members and the holes 19 of the link flanges. The buckets are of uniform width throughout, and correspond to the extreme width between the outermost edges of the outside links for uniformity. The sides 26 are exactly the same in shape, providing for interchangeability, and avoiding necessity for rights and lefts.

The rows of attaching holes of alternating links are off-set inwardly from those of adjacent links a distance equaling the difference in alignment, due to the off-setting of alternate links, so as to bring the holes into alignment when connected, and conforming to suitable templet standard measurement and location of the holes on the back or front plates of the bucket. The upper and lower edges of each bucket and its back wall terminate exactly at the pivoting center of its carrying links, so that, as the links straighten out into strand formation, the edges of the buckets will abut continuously. As shown, the bottom edges of the bucket are slightly spaced apart as at *c* so as to allow for escape of moisture by draining. Any small particles which may pass through such opening will be received in the next lowermost bucket, so as to ensure against any loss of material. In travelling around the sprocket wheels, they will open up, as in Fig. 3, as the links conform to the shape of the sprocket wheels.

The elevator boot 5 is of concave construction through its main bottom cavity, having a receiving front portion curved concentric with the center of the shaft 11, as at 31, and a rear portion 32 of longer arc.

In operation, the bucket edges approach downwardly through the rear cavity with ample clearance, until they arrive at about the center, when they begin to rise in filling by scooping up the contents of the boot, conforming closely to the inner contour of the boot. The advantage of such construction is that it ensures even filling of the buckets and avoids crushing the coal, or impairing the edge of the bucket. At each outer side, the boot is enlarged by side bays 33 for clearance of the extended flanges 24 of the sprocket wheels, as in Fig. 4, so that the width of the boot may be maintained at substantially the width of the buckets themselves, with slight clearance. By this means, I avoid any grinding or crushing of the material, or injury to the buckets, at the sides.

The construction and operation of the apparatus will be readily understood and appreciated from the foregoing description. It provides a very strong and serviceable construction, capable of continuous operation, and not liable to get out of order. When used with flights for conveyor purposes, the operation of the links with similarly attached flights, either abutting or overlapping, in connection with the trackways and sprockets, is substantially the same as in the case of buckets.

It will be noted also that the buckets are in a continuous abutting series, and that each bucket is connected with its links at each side for substantially the full length of both bucket and link. Also, that the links being continuously straight from one end to the other, provide for a continuous bearing edge on the trackway, as well as for practically continuous connection with the buckets or conveyor slats. The resulting effect and advantage is in providing for a continuously firm and substantial supporting foundation and carrying mechanism for the structure, either in conveyor or elevator form.

In Figs. 9 and 10 I show a modified construction in which a portable section of conveyor A' is utilized for easy location under a car, but extending across over the rails, for temporary use. In such arrangement, the conveyor chain 16' rides along the flanges of upper and lower angle members 6', 7', under the power imparted by the sprocket of head shaft 10' driven by chain 12' from the elevator foot shaft 11.

The middle portions of supporting runners 6'-7' are brought closely together for compact construction, widening apart towards each end; as shown, for clearance of the terminal sprockets, and incidentally inclining the conveyor at its receiving and delivery ends.

The entire structure is framed together and provided with supporting legs 35 and inwardly inclined sides 36 sufficiently long to

receive the contents of car 3' which rests by its wheels on the rails 2' of the track. By this arrangement, coal or other material is received and delivered to the conveyor and carried thereby and delivered over the end of the conveyor to the elevator boot. When the car is emptied, the conveyor section is easily lifted away, allowing shifting of the empty and next loaded car, when it 16 may be replaced and the operation resumed.

It will be understood, of course, that in adapting the chain, hexagonal or octagonal sprocket wheels may be substituted, if desired, with the flat sides suitably designed 15 for the length of the links, and that other changes or modifications may be made by the skilled mechanic, within the scope of the following claims.

What I claim is:

20 1. In combination, an elevator provided with supporting angle shaped trackway members and bottom and top sprocket wheel members having faces and flanges in alining conformation with the bearing faces 25 and flanges of the trackway members, pairs of double-sided link chains engaging said sprocket wheel members and trackway members by their edges, driving gearing therefor, a continuous series of buckets extending 30 across and secured to said link chains, a receiving boot for the lower terminal of the conveyor, and a laterally extending conveyor arranged to receive material by gravity consisting of a trackway frame having 35 similar angle shaped runway members for conveyor chains having cross supporting flights, a tail and head shaft and sprockets therefor, and a driving chain connecting said head shaft with the bottom sprocket 40 wheel shaft of the elevator.

2. In combination, an elevator provided with supporting angle shaped trackway

members and bottom and top sprocket wheel members having faces and flanges in alining conformation with the bearing faces 45 and flanges of the trackway members, pairs of double-sided link chains engaging said sprocket wheel members and trackway members by their edges, driving gearing therefor, a continuous series of buckets extending 50 across and secured to said link chains, a receiving boot for the lower terminal of the conveyor, and a laterally extending portable conveyor arranged to receive material by gravity consisting of a trackway 55 frame having similar angle shaped runway members for conveyor chains having cross supporting flights, a tail and head shaft and sprockets therefor, a supporting framework for mounting the conveyor across the 60 rails of a track having inwardly inclined sides leading to the conveyor, and a driving chain connecting said head shaft with the bottom sprocket wheel shaft of the elevator.

65 3. In combination with a pair of spaced apart square sprocket wheels having outermost circular flanges, a series of pairs of double links pivotally connected to provide for cooperation with the sprocket wheel and 70 provided with an inwardly extending flange on each inner link for its full available length with sufficient pivoting clearance, and a bucket mounted across each pair of double links consisting of a back plate extending 75 across all of the link edges and secured to said flanges and of a length co-extensive with the length of the links between their pivoted joints, and provided with outwardly extending side walls and an outermost cross 80 wall.

In testimony whereof I hereunto affix my signature.

SIMEON H. RICKARD.
